(57) **CLAIM**

The ornamental design for a bench, as shown and described.

DESCRIPTION

FIG. 1 is a perspective view of a design for a bench, according to a first embodiment;

FIG. 2 is a left front side view of the design for a bench;

FIG. 3 is a right front side view of the design for a bench;

FIG. 4 is a left back side view of the design for a bench;

FIG. 5 is a right back side view of the design for a bench;

FIG. 6 is a top view of the design for a bench;

FIG. 7 is a bottom view of the design for a bench;

FIG. 8 is a perspective view of an alternative design for a bench, according to a second embodiment;

FIG. 9 is a right front side view of the alternate design for a bench;

FIG. 10 is a left front side view of the alternate design for a bench;

FIG. 11 is a right back side view of the alternate design for a bench;

FIG. 12 is a left back side view of the alternate design for a bench;

FIG. 13 is a top view of the alternate design for a bench; and,

FIG. 14 is a bottom view of the alternate design for a bench.

The broken lines shown in the drawings depict portions of the bench that form no part of the claimed design. The bench is shown with a symbolic break in the length of a leg. The appearance of any portion of the article between the break lines forms no part of the claimed design.

1 Claim, 14 Drawing Sheets
